UNITED STATES PATENT OFFICE.

FLOYD F. TURNER, OF TOLEDO, OHIO, ASSIGNOR TO THE HAUGHTON ELEVATOR & MACHINE CO., OF TOLEDO, OHIO, A CORPORATION OF OHIO.

DOOR LOCK FOR ELEVATORS.

Application filed January 6, 1921. Serial No. 435,383.

To all whom it may concern:

Be it known that I, FLOYD F. TURNER, a citizen of the United States of America, residing at Toledo, Lucas County, Ohio, have invented new and useful Door Locks for Elevators, of which the following is a specification.

This invention relates to a control or control and lock or locks for doors or gates. 10 This invention has utility when incorporated for restricted operation, especially in connection with an interlock for slidable landing doors for elevators.

Referring to the drawings:

15 Fig. 1 is a wiring diagram of the interlock feature of an embodiment of the invention;

Fig. 2 is a view with parts broken away of the landing door having the door coacting mechanism associated therewith;

Fig. 3 is a plan view of features of the lock;

Fig. 4 is a side elevation of the lock of Fig. 3, showing the interlock associated therewith, with the door in closed position;

Fig. 5 is a fragmentary view of the lock and interlock shifted by door opening;

Fig. 6 is a fragmentary view showing attempt at door shift, with the lock holding the door against such shifting; and

Fig. 7 is a section on line VII—VII, Fig. 4.

Elevator shaft 1 is shown as provided with a plurality of landings 2. In this shaft 1 is disposed elevator car 3 having controller 4, central line 5 which extends from supply line 6. Shifting of the controller 4 say to terminal 7 permits current to flow from between lines 6 and by terminal 7 through line 8 past terminals 9, 10, closed by interlock switches 11 to energize coil 12 to main switch 13, for this circuit is completed from the coil 12 to main supply line 14. In this shifting of the controller 4 for up-direction travel, the next position connections to line 15 energizing up-direction switch coil 16 of up-direction switch 17, which permits current flow from power supply lines 14, 18, to main elevator driving motor 19, a third line being connected there-to by main switch 12. This main elevator motor 19 is on shaft 20 connected to drive drum 21 having line 22 extending to elevator car 3. This line 22 passing about the drum 21 extends to counterweight 23. For re-

verse of current and direction travel of the elevator car 3 in the elevator shaft 1, the controller 4 is thrown in the opposite direction. The first contact 24 connects to main direction switch 12 by line 8 past interlock switches 11, while further throwing of this controller 4 to line 25 serves to energize coil 26 of up-direction switch 27 for reversing the supply of current to the motor 19 in effecting downward direction driving for the car 3 in the shaft 1.

Access to the car 3 at the landings 2 is normally closed by landing door 28 mounted to slide in guides 29 (Fig. 2). The landing door or gate 28 is herein shown as provided with a ledge or cam 30 upon which is disposed to rest bar 31 having offset portion 32 to a horizontally extending portion 33 having slot 34 therein. This bar 31 normally rests upon the ledge 30 of the elevator landing door 28, and as the door 28 is shifted toward closed position, this ledge 30 coacts with projection 34' in shifting the bar 31 in the direction the door is traveling toward closed position. This shifting causes pin 35 to move in the slot 34 toward the offset portion 32 of this bar 31. In an opening movement of the door 28, the ledge 30 remote from the projection 34' strikes incline 36 of the bar 31 and with the bar 31 not intercepted, this incline 36 is of such pitch that this bar 31 is, in the continued opening movement of the door, shifted along with the door 28, as the weight of the bar and the angle of friction of the incline 36 are sufficient to have it so move for a short distance, say one or two inches. Then the bar 31 engages downwardly extending latch 37 on bar 38 parallel to this bar 31. This bar 38 is an arm of an angle lever having a fixed bearing 39 carrying bar 40 extending transversely to the arm 38 and to which the arm 38 is connected by pins 41 in the line of the bar 31, and slightly above the fixed fulcrum 39.

Nuts 42 serve to fix in the slot 34 of the horizontal portion 33 of the bar 31 a pivot pin 43 which has loosely mounted thereon and spaced from the bar 31 a trigger 44 normally held in horizontal position by counterweight 45. When the door 28 is pulled toward opened position, and the car 3 is within a determined range of a landing 2, say in a push button installation within three or four inches of the floor either

way, while in a driver controlled installation within six or eight inches of the floor either way, an interceptor or bar 48 carried by the car 3 may be in position to be struck by the trigger 44 as the door 28, in opening, pulls the bar 31. This response to further shifting of the bar 31 in the direction of opening travel of the door 28, causes the pull or opening action of the door 28, 10 transmitted through the ledge 30, to cause such ledge 30 to ride along the incline 36, to lift the end of the bar 31. This upward lifting of the bar 31 causes this bar to go against offset 47 of the bar 38 so that as 15 the bar 31 is moved simultaneously, the bar 38 is also lifted and the travel of the door 28 clears the latch 37 of the bar 38. These bars 31, 38, as lifted swing on fixed fulcrum 39. Depending arm 40 of this angle lever 38, 20 40, has switch 11 normally closing contacts 9, 10, of interlocking switch for the bar 38 acts as a gravity holder. This interlocking switch in practice is desirably located in box 48 which may be sealed by an 25 electrical or insurance inspector as a reliable safety device for as long as the gate or door 28 is open, the bar 38 may not be lowered, this bar 38 riding on the ledge 30. Accordingly, the elevator car 30 cannot be started from the controller 4 in the car while the landing gate is open to such an extent that the latch 37 rides upon the ledge 30.

The leeway between the closed position of 35 the door, wherein the bar 30 is spaced from the latch 37, will permit operation of the controller for starting or stopping the car in lifting or approaching the landing, and this distance may be adjusted as found desirable in practice within safety limits. At 40 once the door 28 is closed, the long arm 38 as a counterweight swings the switch 11 into closing position to permit the controller 4 to energize the main switch and thereby 45 operate the elevator car driving motor 19. Any attempt to open the door 28 when the elevator car 3 is away from the landing beyond the limit determined by interceptor 46 on the car 3 or when the car is moving 50 appreciably even opposite a landing, the trigger is ineffective as shown in Fig. 6 for the shifting of this door does not rock the bar 31 but slides this floating throw member or bar 31 because the trigger 44 does not hold 55 this bar 31 to act with the angle levers 38, 40.

There is accordingly provided in this installation a structure having maximum of safety provisions in connection with the 60 widest range of installation in most compact locations for general application to different types of structures.

It is to be noted in operation that the bar 31 is herein shown as a floating throw member carrying a gravity set trigger.

What is claimed and it is desired to secure by United States Letters Patent is:—

1. A movable door provided with a ledge, a bar disposed to be shifted by movement of the door, a latch, and an intercepting means 70 movable relatively to the bar to control shifting of the door to operate the latch.

2. A movable door provided with a ledge, a bar disposed to be shifted by movement of the door, an interlock connected to be controlled from said bar, and an intercepting means movable relatively to the bar to control shifting of the door to operate the interlock. 75

3. A movable door provided with a ledge, 80 a bar disposed to be shifted by movement of the door, a latch, an intercepting means movable relatively to the bar to control shifting of the door to operate the latch, and an interlock connected to be controlled by 85 said latch.

4. An elevator shaft provided with landings, a landing door at the landing, said door having a ledge, an elevator car in the shaft, a power drive for the car, a controller 90 in the car for the drive, a cut-out switch rendering the control ineffective, an interceptor, carried by the car, and a bar mounted to be shifted by the door ledge on movement of the door, said interceptor being disposed when the door is opened to cause the bar to open the switch. 95

5. A lock for a door comprising a floating throw member, a latch, and an interceptor coacting upon door movement to shift the 100 throw member to operate the latch.

6. A lock comprising a latch member, a floating throw member, an interceptor, and an actuator for the throw member shifting the throw member independently of the interceptor to render the latch ineffective. 105

7. A lock comprising a latch member, a floating throw member, a relatively movable interceptor, and an actuator for the throw member shifting the throw member as controlled by the interceptor to operate the latch. 110

8. A lock comprising a latch member, a floating throw member provided with a gravity set trigger, an interceptor coacting with the trigger, and an actuator for the throw member to bring the trigger against the interceptor for shifting the throw member to actuate the latch. 115

9. A lock comprising a latch member, a floating throw member provided with a gravity set trigger, an interceptor coacting with the trigger, an actuator for the throw member to bring the trigger against the interceptor for shifting the throw member to actuate the latch, and a switch controlled by the latch member. 120

10. A trigger carrying member, a door movable to effect shifting of the member, a trigger carried by the member, an intercep- 125 130

tor for the door actuated member, and a switch operable by the trigger as the member is controlled by the interceptor.

11. A door, a member shiftable upon movement of the door, a trigger carried by the member, a latch for holding the door, and an interceptor for controlling the member through the trigger to shift the latch to release the door.
- 10 12. An elevator car, a shaft in which the car is movable, said shaft having a landing, a landing door, a lock for the door, an in-

terceptor carried by the car, and movable means with which the interceptor may contact when the car is at the landing for holding the lock for door release, said movable means being rockable by the interceptor upon door release attempt during car travel past the landing, thereby rendering the lock effective to hold the door against opening under such condition. 15

In witness whereof I affix my signature.

FLOYD F. TURNER.
